(57) **CLAIM**

The ornamental design for a stepladder, as shown and described.

DESCRIPTION

FIG. 1 is a front perspective view of a stepladder showing our new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof;

FIG. 8 is an enlarged view of the portion indicated by lines 8-8 in FIG. 1;

FIG. 9 is an enlarged view of the portion indicated by lines 9-9 in FIG. 3;

FIG. 10 is an enlarged view of the portion indicated by lines 10-10 in FIG. 4;

FIG. 11 is an enlarged view of the portion indicated by lines 11-11 in FIG. 6;

FIG. 12 is an enlarged view of the portion indicated by lines 12-12 in FIG. 7;

FIG. 13 is an exploded perspective view thereof; and,

FIG. 14 is a rear view thereof in a collapsed position.

The features shown in broken lines in the drawings depict environmental subject matter only and form no part of the claimed design. The dot-dashed lines define the boundaries of the claimed design and form no part thereof.

1 Claim, 14 Drawing Sheets
